INVENTOR
BY *Victor J. Evans*

WITNESS *W. Thompson*

ATTORNEY

UNITED STATES PATENT OFFICE.

CLARENCE E. PILE, OF PARSONS, KANSAS.

WRENCH.

Application filed November 7, 1927. Serial No. 231,731.

This invention relates to improvements in wrenches and has for an object the provision of means for permitting rapid adjustment of the movable jaw of a wrench, and for holding 5 the said jaw against movement by pressure upon the handles or grips of the wrench.

Another object of the invention is the provision of means of the above character which may be applied to pipe wrenches and other 10 tools, as well as to monkey wrenches.

With the above and other objects in view, the invention further includes the following novel features and details of construction, to be hereinafter more fully described, illustrated in the accompanying drawings and 15 pointed out in the appended claims.

In the drawings:—

Figure 1 is an elevation of the invention.

Figure 2 is a similar view with the movable jaw partly broken away and shown in 20 section and the parts shown in engaged position.

Figure 3 is a view partly in section and partly in plan.

Figure 4 is a section on the line 4—4 of 25 Figure 1.

Figure 5 is a similar view on the line 5—5 of Figure 2.

Referring to the drawings in detail where- 30 in like characters of reference denote corresponding parts, the invention as shown comprises a pair of relatively movable members which include shanks 10. These shanks are formed of flat metal and are pivotally connected at one end by means of a pivot 11, the latter also being utilized to secure the sta- 35 tionary jaw 12 which is recessed as at 13 to receive the ends of the shanks. Extending from the other ends of the shanks are handles 40 14, while slidably mounted upon these shanks is a relatively movable jaw 15. This jaw is provided with an opening 16 for the passage of the shanks 10 and this opening is slightly greater in area than the combined cross sec- 45 tional areas of the shanks.

When the handles are in the position shown in Figure 1 of the drawings, the jaw 15 may be easily moved along the shanks for adjustment relative to the jaw 12. As soon as the jaws have been satisfactorily adjusted to a 50 nut or other object, the handles 14 will be gripped so that they will be moved relatively inward, whereupon, the shanks will be moved to the position shown in Figures 2 and 5 so as to frictionally engage the opposite walls 55 of the opening 16 and hold the jaw 15 in position.

The invention is susceptible of various changes in its form, proportions and minor details of construction and the right is here- 60 in reserved to make such changes as properly fall within the scope of the appended claims.

Having described the invention what is claimed is:—

1. A tool comprising a pair of pivotally 65 connected members, handles at one end of the members, a stationary jaw, and a jaw having an opening therethrough to slidably receive the pivotally connected members to permit relative adjustment of the jaws and to hold 70 the movable jaw in position when the handles are pressed relatively inward through engagement of said members with the walls of the opening of said jaw.

2. A tool comprising a pair of pivotally 75 connected members, a handle at one end of each of the members, a stationary jaw, a relatively movable jaw mounted upon said mem- 80 bers and held against movement by the mem- bers when the handles are pressed relatively inward.

3. A tool comprising a pair of members pivotally connected at one end, a stationary jaw secured to the pivoted ends of the mem- 85 bers, and a relatively movable jaw slidable upon said members and engaged by and held against sliding movement when said members are pressed relatively inward.

In testimony whereof I affix my signature.

CLARENCE E. PILE.
